UNITED STATES PATENT OFFICE.

JAMES T. ATWOOD, OF ROCKFORD, ILLINOIS.

AUTOMOBILE-DOOR BUFFER.

1,299,416.

Specification of Letters Patent.

Patented Apr. 8, 1919.

Application filed April 23, 1918. Serial No. 230,215.

To all whom it may concern:

Be it known that I, JAMES T. ATWOOD, a citizen of the United States, residing at Rockford, in the county of Winnebago and State of Illinois, have invented certain new and useful Improvements in Automobile-Door Buffers, of which the following is a specification.

This invention pertains to door buffers, and particularly to buffers for use on automobile bodies for the purpose of cushioning the closing movements of the doors and for preventing rattling of the doors when the vehicle is in motion.

15 In buffers of this character it is highly desirable that the buffer be adjustable, in order that it may be accurately positioned with respect to the door, for if it is disposed outwardly a little too far it is extremely difficult to close the door against the buffer sufficiently to cause it to latch; and on the other hand, if the buffer is disposed too far inwardly it will not prevent the door from rattling in its frame. Furthermore, since 25 these buffers are subjected to very hard usage and wear, it is desirable that the buffers be adjustable to take up this wear, and in order to increase the life and usefulness of the buffer, it is also very advantageous to 30 employ a buffer of the roller type which is rotatable so as to continuously present new buffing surfaces into operative position with respect to the door.

It is also desirable that the buffer be adjustable vertically as well as horizontally, for the reason that the buffers are relied upon to prevent vertical rattling movements of the door as well as horizontal movements, and therefore, vertical adjustability renders 40 the buffer much more effective and satisfactory than it would be, if capable of horizontal adjustment only.

One of the primary objects of my present invention is to provide a buffer particularly 45 suitable for use on automobile bodies which shall be capable of adjustment both vertically and horizontally, and in fact, in any direction radially with respect to the axis about which the buffer rotates.

50 Another object is to provide an adjustable buffer which shall also be capable of rotation so as to present fresh wearing surfaces into operative position.

Still another object is to provide a buffer 55 which will be simple in construction, cheap to manufacture and assemble, and effective

and durable in operation, and which can be readily applied and quickly and easily adjusted by the car manufacturer and whenever adjustment is subsequently necessary. 60

For the purpose of facilitating an understanding of my invention, I have illustrated on the accompanying drawing a preferred embodiment thereof, from an inspection of which, when considered in connection with the following description, the structure, function and many of the attendant advantages of my improvements should be readily appreciated.

Referring to the drawings:

Figure 1 is a horizontal sectional view through a door and its frame equipped with my improved buffer;

Fig. 2 is a view taken on the line 2—2 of Fig. 1, showing the buffer in one of its extreme adjusted positions;

Fig. 3 is a similar view, the door structure however, being omitted, and the buffer being adjusted to an extreme position in the opposite direction from the adjustment disclosed in Fig. 2; and

Fig. 4 is a view similar to Fig. 3, showing in full and dotted lines two other adjusted positions of the buffer.

On the drawings, reference character 5 indicates generally a frame structure, which in the present instance is the door frame of an automobile body, and 6 indicates the door, which as shown in Fig. 2, is provided with a recess 7 on its swinging edge adapted to receive the buffer. The buffer device is fastened to the edge of the door frame, as shown in Fig. 1, and when the door is closed the buffer will be snugly seated in the door recess 7 so as to hold the door from rattling movements either in horizontal or vertical directions.

The buffer device consists, primarily, of a buffer member 8 constructed of rubber or other resilient material in cylindrical form provided with a centrally disposed aperture, and on its outer end with a depression or recess 9. A metallic bushing 11 is arranged in the central aperture of the buffer member and forms the arbor on which the buffer member rotates. This bushing, as will be evident from Fig. 1, is slightly longer than the thickness of the buffer portion through which it projects and the bushing is secured to the door frame by means of a wood screw 12 and a washer 13 interposed between the head of the screw and the outer end of the

bushing 11. Since the bushing is slightly longer than the material of the buffer through which the bushing is inserted, it will be evident that when the screw is tightened up the bushing will be firmly clamped between the washer 13 and the face of the frame 5, while the buffer member will be retained on the bushing or arbor by the washer 13 but will be free to rotate on this arbor. 5
10 When the screw is tightened up the inner end of the bushing will be forced slightly into the wood of the frame 5 so as to assist in preventing lateral movement of the bushing; but I have found that in some instances 15 when the wood of the frame is too soft it is desirable to interpose between the frame and the inner end of the bushing, a washer, preferably made of fiber, which will prevent the end of the bushing from entering into the 20 frame and forming a dent or groove of sufficient depth to interfere with subsequent adjustments of the bushing.

It will be observed that the bushing is considerably larger than the shank of the fastening screw 12, and these relative proportions are employed for the express purpose of providing for adjustability of the buffer with respect to the fastening screw. When the screw is loosened, it will be manifest that 25 the bushing and the buffer member carried thereby may be adjusted in any radial direction with respect to the screw so that the buffer may be adjusted horizontally between the two extreme positions shown in Figs. 2 30 and 3, or vertically between the two extreme positions shown in full and dotted lines respectively of Fig. 4, or may be adjusted an equal amount in any diagonal direction intermediate the adjusted positions shown in 35 40 these figures.

This adjustability in any direction enables the buffer to be positioned with extreme accuracy, so that when disposed in the recess of the closed door it will hold the door 45 against horizontal or vertical vibratory movements, which result in unpleasant rattling of the doors. The buffer in any of its adjusted positions is capable of rotation about its arbor so as to continually present 50 new operating surfaces, thereby materially increasing the life of the buffer; and whenever it may be desirable either as the result of wear or for other reasons, to alter the position of the buffer on the frame, this adjustment may be very quickly and easily 55 accomplished by simply loosening the fastening screw and moving the buffer member bodily with respect to the screw in any direction into the desired position, whereupon

it may be secured in the adjusted position 60 by simply tightening up the screw so as to clamp the bushing in position, which however, as has been previously explained, does not prohibit or interfere with the free rotation of the buffer member. 65

It is believed that my invention in its preferred embodiment will be understood from the foregoing without further description, and it should be obvious that various modifications in the structure might be resorted 70 to without departing from the universal adjustability of the device or exceeding the scope of the invention as defined in the appended claims. 75

I claim:

1. A buffer device comprising a cylindrical bushing, a roller buffer freely rotatable thereon, and means for fixedly clamping said bushing to a frame or the like and permitting radial adjustment of said bushing and 80 buffer upon said clamping means without detachment from said frame.

2. A buffer device comprising a roller, and a fastener for rotatably securing said roller to a frame or the like, said fastener 85 including means to permit radial adjustment of said roller in any direction upon the fastener.

3. A buffer device comprising a rotatable buffer having an opening therethrough, a bushing in the opening in the roller and projecting at opposite faces thereof, the buffer being rotatable upon the bushing, and a headed fastening extending through the bushing, the shank of the fastening being of 95 less diameter than the internal diameter of the bushing, and the head of the fastening exceeding the internal diameter of the bushing to lie against the adjacent end thereof and clamp the bushing rigidly between the 100 head and the support to which the buffer is applied, whereby, when the fastening member is loosened, the bushing and the rotatable buffer may be adjusted radially in any direction upon the fastener. 105

4. A buffer device of the character described, comprising a roller, a bushing through the roller and about which the roller is freely revolvable, and fastening means of less diameter than the bushing and passing loosely through the bushing for securing the same to a part of a closure or its casing, and when loosened, allowing the bushing and its roller to be adjusted radially in any direction relatively to the fastening means. 110

JAMES T. ATWOOD.
